UNITED STATES PATENT OFFICE.

FREDOLF J. PETERSON, OF ALLIANCE, OHIO.

CREDIT-CABINET.

No. 913,911.

Specification of Letters Patent.

Patented March 2, 1909.

Application filed September 8, 1908. Serial No. 452,131.

To all whom it may concern:

Be it known that I, FREDOLF J. PETERSON, a subject of the King of Sweden, residing at Alliance, in the county of Stark and State of Ohio, have invented certain new and useful improvements in Credit-Registers; and I do hereby declare that the following is a full, clear, and exact description of the same, reference being had to the accompanying drawings, making a part of this specification, and to the numerals of reference marked thereon, in which—

Figure 1 is a perspective view, showing a portion of the cabinet frame, and portions of the credit slip holding leaves, some of said leaves being illustrated in elevation and others in lowered position. Fig. 2 is a perspective view of a detached set of credit slip holding leaves showing one set of the parallel notched connecting bars detached. Fig. 3 is a vertical section, showing all of the credit slip holding leaves in elevated position and the cabinet closed. Fig. 4 is an enlarged view showing transverse sections of the credit slip holding leaves and the slip holding clips connected thereto, also illustrating the manner of connecting the notched sets of parallel bars to the supporting bars. Fig. 5 is a view showing a portion of one of the credit slip holding leaves and the credit slip holding clips, said credit slip holding clips detached but their parts bent in position to connect the same to the credit slip holding leaves. Fig. 6 is an enlarged view of one of the credit slip holding leaves showing two credit slip holding clips properly connected. Fig. 7 is a view, showing one of the credit slip supporting bars and one set of the parallel notched bars illustrating a portion of one of said bars broken away.

The present invention has relation to credit cabinets and it consists in the novel arrangement hereinafter described and particularly pointed out in the claims.

Similar numerals of reference indicate corresponding parts in all the figures of the drawings.

In the accompanying drawings, 1 represents the cabinet frame or casing which may be of the form shown and preferably is of the form shown so that the different parts can be connected and operated, but I do not desire to be confined to any specific formation of frame, except that it must be so formed that the parts hereinafter described can be

properly connected and operated. To the desk or front 2 are attached the bottom or lower ends of the credit slip supporting bars 3 their top or upper ends being attached to the inner back 4 as illustrated in Figs. 1 and 60 3. For the purpose hereinafter described, the supporting bars 3 are provided with the angled tangs 5, which angled tangs are for the purpose hereinafter described.

For the purpose of pivotally connecting 65 a series of credit slip holding leaves 6 together I provide two sets of spaced notched bars 7, which bars are held in proper spaced relationship with reference to each other by means of the rivets 8 or their equivalents, 70 which rivets also serve the purpose of providing means for temporarily connecting the notched bars 7 to the supporting bar 3 by means of the angled tangs 5, said notched bars being connected by locating the notched 75 bars upon the supporting bars 3 and afterward moving said bars downward and sliding said bars into the position to bring the rivets 8 under the horizontal portions of the angled tangs 5 as best illustrated in Fig. 4. 80 It will be understood that an upward and backward movement must be given to the bars 7 in order that they may be detached and removed from the cabinet frame proper, together with the credit slip holding leaves 85 6 and their clips which credit slip holding leaves are pivotally attached to the notched bars as hereinafter described. Each credit slip holding leaf 6 is provided with the short lugs 9 which are entered between the sets 90 of parallel bars 7 through which bars and lugs the pins or rivets 10 pass, thereby pivotally attaching the credit slip holding leaves to the notched bars 7. The notched bars when placed in an inclined position as 95 illustrated in the drawings will support the credit slip holding leaves 6 in what might be termed stepped relationship with reference to each other as best illustrated in Figs. 1 and 3.

It is well understood that in credit cabinets, it is desirable to temporarily attach credit slips to the credit slip holding leaves and in order to provide for this I provide a peculiarly constructed clip 11, which clip is 105 connected to the credit slip holding leaves as follows: The base of the clip 11 is bent substantially at right angles to the clip portion whereby the part 12 is produced, from which part the integral tangs 13 and 110

14 are extended. The tangs 13 while in alinement with the base 12, as illustrated in dotted lines in Fig. 5 are passed through the slots 15 formed in the leaves 6, after which they are bent into the positions illustrated in full lines. The tangs 14 serving to brace the clip proper so that the full spring energy of the clips is maintained or in other words no pivotal or substantially no pivotal action is permitted as between the leaves 6 and the clips 11 after they have been properly connected. It will be understood that the slots 15 should be formed of a sufficient width that the tangs 13 of two clips can be passed through said slots when in the position shown in dotted lines Fig. 5. When it is desired to place clips upon both sides of the credit slip holding leaves and in exactly opposite positions the tangs 13 of one clip are bent upward and the tangs 13 of the other clip bent down whereby the tangs are properly connected.

It will be understood that in credit cabinets it is desirable to close the credit cabinet from time to time and in order to provide for this the flexible curtain 16 is provided, to which curtain is attached at its top and bottom the chain 17, the links of which chain engage the sprocket wheel 18, which sprocket wheel is loosely mounted upon the bar 19, which bar is connected to the side members of the cabinet frame or their equivalents. To the sprocket wheel 18 is attached one end of the spring 20 and the opposite end of the spring is connected to the bar 19. When the curtain 16 is brought into the position illustrated in Fig. 3 which is the position to close the cabinet, the sprocket wheel 18 will be rotated thereby winding the spring 20 and giving said spring tension, which force is utilized to elevate the curtain when it is desired to open the cabinet. For the purpose of holding the chain 17, a second sprocket wheel 21 is provided which sprocket wheel is located above the inner back 4, thereby guiding the chain as the curtain 16 is brought into the position to open the cabinet.

It will be understood that by notching the sets of parallel bars 7 the lugs 9 can be formed

somewhat shorter than they otherwise could, thereby bringing the pivotal points of the credit slip holding leaves near their bottom or lower edges and at the same time preventing any binding of the credit slip holding leaves as between themselves. By providing the open notches or recesses in the sets of the parallel bars 7 the hinged edges of the credit slip holding leaves can be brought close to the bars and at the same time provide room for the extreme bottoms of the credit slip holding leaves when they are brought into a horizontal position as illustrated in Fig. 2 and at the same time providing means whereby the pivotal points of the credit slip holding leaves are in close proximity to the bottom or lower edges of the credit slip holding leaves.

Having fully described my invention what I claim as new and desire to secure by Letters Patent, is—

1. In a credit cabinet of the class described, a cabinet frame, a series of slip holding leaves provided with lugs, fixed supporting bars secured to the cabinet frame, said bars inclined forward and downward, angled tangs secured to said bars, spaced parallel bars provided with notches, the lugs of the credit slip holding leaves being pivotally attached to said bars, and means adapted to hold the parallel bars in engagement with the angled tangs, substantially as and for the purpose specified.

2. In a credit cabinet of the class described, a cabinet-frame, a series of credit slip holding leaves, notched bars, inclined supporting bars fixed to the cabinet-frame, and means for temporarily connecting the notched bars to the inclined supporting bars, the credit slip holding leaves being pivoted to the notched bars, substantially as and for the purpose set forth.

In testimony that I claim the above, I have hereunto subscribed my name in the presence of two witnesses.

FREDOLF J. PETERSON.
